UNITED STATES PATENT OFFICE

103,683

DESIGN FOR A MUSICAL INSTRUMENT

William E. Lednum, Easton, Md., assignor to
Plakola Corporation, Easton, Md., a corpora-
tion of Maryland

Application January 26, 1937, Serial No. 67,295

Term of patent 7 years

To all whom it may concern:—

Be it known that I, William E. Lednum, a citizen of the United States, residing at Easton, in the county of Talbot and State of Maryland, have invented a new, original, and ornamental Design for Musical Instruments, of which the following is a specification, reference being had to the accompanying drawing, forming part thereof.

Figures 1, 2 and 3, are respectively, the front, end and rear views of a musical instrument, showing my new design.

I claim:

The ornamental design for a musical instrument, as shown.

WILLIAM E. LEDNUM.
